RAIL ANCHOR

Harold G. Warr, Park Ridge, Ill., assignor to
 Poor & Company, Chicago, Ill., a corporation
 of Delaware

Application June 18, 1938, Serial No. 214,423

4 Claims. (Cl. 238—327)

This invention relates to a new and improved rail anchor adapted to grip the base portion of a rail and abut against a side face of an adjacent cross-tie.

5 Rail anchors of the class to which this invention appertains are ordinarily formed with one or more jaws which overlie the top surface of a rail base at one side of a cross-tie and consequently engage the rail base at a location where 10 there is no support for the rail directly beneath the overlying jaw. The said overlying jaw, or jaws, of such anchors, heretofore made, have been relatively thick at a location directly above the thin marginal portions of the base which 15 project beyond the side faces of the rail head. Such constructions are objectionable in that the jaws are ordinarily so formed that a derailed wheel, when rolling on the said thin marginal portion of a rail base flange will strike the relatively 20 thick portion of the anchor jaw which directly overlies the thin marginal portion of the rail base flange. This condition is present regardless of whether the wheel is so derailed that the wheel flange is supported on the rail base 25 flange or whether the tread portion of the wheel is supported thereon. In either event, the impact of the derailed wheel against the relatively thick jaw of the anchor at a location overlying the thin edge of the rail base tends to punch 30 the thick portion of the anchor jaw through the rail base flange. The same damage results to the rail when the thick upper jaw of the anchor is struck at any location, for example, at some point beyond the outer edge of the rail base 35 flange, since the downward movement of said jaw, under the force of the impact, carries the relatively thick unyielding portion of the jaw through the thin edge portion of the rail base.

A principal object of this invention is to provide 40 new and improved rail anchor constructions which will overcome the objection above referred to.

Another object is to provide a rail anchor in which the jaw portion overlying the rail base 45 flange is so formed as to provide the necessary strength and rigidity for effecting a highly efficient grip on the rail base, but which, when struck by a derailed wheel, will be dislodged from the rail and/or minimize the punching or shear- 50 ing stresses on the rail flange when the anchor is struck by a derailed wheel.

Another and more specific object is to provide 55 a rail anchor construction which makes it practicable to reduce the vertical thickness of the anchor jaw directly above the thin edge por-

tion of the rail base flange without sacrificing the strength and rigidity in the jaw which is necessary to produce the desired gripping action thereon on the rail and at the same time provide a jaw construction of sufficient height and resilience that it will be readily dislodged from the base portion of a rail by the impact of a derailed wheel when the wheel strikes the anchor jaw at any location beyond the outer edge of the rail base flange.

According to the present invention, the rail anchor jaw or jaws, as the case may be, which overlie the top surface of the rail base, are of hook configuration and are otherwise so formed as to confine their engagement with the rail 15 base at a location near the edge of the base flange. The thickness of the jaw gradually decreases toward the end, whereby the relatively thin end only of the said jaw overlies the rail base flange. The increasing thickness of the jaw 20 toward the bend of the hook provides the required strength to resist any tendency which the upper and lower jaws may have to spread apart when they are subjected to increased tension, for example, when the body of the anchor 25 is pressed against the side face of the cross-tie during the presence of creeping pressure on the rail. The said increasing thickness of the jaw also elevates the outer end of the jaw relative to the rail engaging end thereof so that the outer 30 and higher end of the jaw will be more likely to receive the impact of a derailed wheel than the thinner inner end portion thereof. The impact of a derailed wheel against any portion of the anchor jaw at a location beyond the edge of the 35 rail base will readily distort the thin end portion of the jaw overlying the rail base and thereby dislodge the anchor from the rail.

When an anchor jaw is formed in accordance 40 with this invention, a derailed wheel can strike the thin inner portion of the jaw only in the event that the wheel is so derailed that the flange thereof is supported on the base flange 45 of the rail. Such condition, however, would be rather infrequent since the edge of a rail base flange only projects from one to one and one-half inches beyond the side face of the rail head. Consequently the greater proportion of damage is caused by wheels striking the outer end portion of the anchor jaw and thereby forcing the 50 heavy portion of the jaw overlying the rail base through the thin edge portion of the base. In the event, however, that a wheel flange of a derailed wheel should be so supported on the flange 55 of the rail as to strike the thin inner edge of the

anchor jaw of the present invention, the reduced thickness of the jaw will correspondingly minimize the punching and shearing stresses imposed on the rail flange.

5 Other objects and advantages of the invention will be apparent from the detailed description of the two embodiments of the invention shown in the accompanying drawings, wherein

10 Fig. 1 is a plan view of the base portion of a railroad rail showing a rail anchor constructed in accordance with this invention applied thereto.

15 Fig. 2 is a cross-sectional view through a railroad rail showing the anchor device in side elevation and illustrating the manner in which a derailed wheel will ordinarily contact the outer thicker portion of the rail engaging jaw of the anchor.

20 Fig. 3 is a view similar to Fig. 2, but illustrating the jaw end of the anchor applied to the outer base flange of the rail and shows a wheel derailed and supported on the said outer flange of the rail.

25 Fig. 4 is a sectional view taken on line 4-4 of Fig. 3, and

Fig. 5 is a view in perspective of a slightly modified rail anchor construction.

Referring first to Figs. 1 to 4 inclusive of the drawings: 10 designates a railroad rail, 11 a cross-tie, 12 a metal tie plate interposed between the top face of the cross-tie and the base portion of the rail, and 13 designates a rail anchor made in accordance with this invention applied to the rail in a position to abut against a vertical face of the cross-tie 11.

30 The anchor device 13, as shown herein, is made from a steel bar, one end of which is bent into hook form to provide an upper jaw 14 and a lower jaw 15 adapted to be driven transversely of the rail into resilient gripping engagement with the top and bottom surface of one base flange of the rail. The other end of the bar extends across beneath the rail base and is provided with a locking shoulder 16 which engages the vertical edge of the other base flange of the rail. The under-rail body portion of the anchor abuts against a side face of the cross-tie 11. It is preferably bowed downwardly, as indicated at 17, so as to engage the side face of the cross-tie 50 at a suitable distance below the upper edge thereof. The upper jaw 14 bears upon the top surface of the rail-base flange at a location spaced inwardly from the bearing of the lower jaw at the edge 18 of the rail base flange, there being 55 preferably a clearance between the said upper jaw 14 and the upper corner portion of the rail base flange engaged. With this arrangement of the jaws, the resilient pressure developed by driving the jaws to their applied position effects a turning movement of the anchor about the bearing 18 of the lower jaw and thereby holds the shoulder end 16 of the anchor in its locking position. The bend 19 of the hook is spaced a substantial distance outwardly from the rail base so that 60 the upper jaw may be formed of suitable length to permit the desired resilient flexing of the jaw and at the same time confine the bearing of the jaw on the rail to a location near the edge of the base flange.

65 A shoulder 20, formed by offsetting the lower jaw vertically, abuts against the edge of the rail base and serves as a positive stop to limit the applying movement of the anchor and thereby insures the proper positioning of the upper jaw 70 near the edge of the base flange of the rail.

The hook portion of the anchor is formed to effect a relatively uniform distribution of the flexing which normally occurs in the bend 19 and the upper jaw and at the same time provide an improved construction which will prevent notching or other damage to the rail flange when the jaw end of the anchor is struck by a derailed wheel and which will also function to increase the grip of the anchor jaws on the rail base flange when certain forces are encountered in service. With these purposes in view the metal at the bend 19 is relatively thick so as to prevent the flexing, incident to the vertical tension on the jaw 14, from being localized at the bend. The upper jaw is flattened and widened so as to gradually decrease in vertical thickness and increase in width toward the rail engaging end thereof so that the resistance to flexing of the jaw gradually increases toward the outer end thereof. The height of the bend 19 and the tapered vertical thickness of the jaw 14 are such that the thicker outer end of the jaw 14 extends above the plane of that portion of the thinned inner end of the jaw which overlies the thin marginal portion of the rail base flange. The higher and thicker outer end of the said jaw 14 will, therefore normally receive the impact of a derailed wheel. Such impact will always be received by the outer end of the jaw when the anchor jaw engages the inner flange of the rail in the manner illustrated in Fig. 2. As a result of such impact, the thin end of the jaw overlying the thin marginal portion of the rail base will bend downwardly and permit dislodgement of the anchor without damage to the rail base.

35 When the anchor jaw is applied to the outer flange of the rail and a wheel is so derailed that the flange of the wheel is supported on the marginal portion of the rail flange, as indicated in Fig. 3, so as to pass over that portion of the anchor jaw overlying the rail base flange, the punching or shearing stresses on the rail flange will be minimixed by the fact that the wheel flange, under such circumstances, will strike the relatively thin end portion of the jaw. The likelihood of damage to the rail base flange in such case is further minimized by the fact that the widened end portion of the jaw, which receives such impact, serves to distribute the thrust of the impact over a large area of the rail base 45 flange.

40 The said widened end portion of the jaw 14, in addition to its function of distributing the said impact force over a large area of the rail base flange, makes it practical to form the anchor from relatively lighter bars and at the same time obtain jaw bearing surfaces 21-22 50 of greater width than the normal width of the bar.

45 It will be seen, by inspection of Figs. 1 and 4, 60 that the depth or vertical dimensions of the bar is greater than the horizontal thickness and that the widened end of the upper jaw projects beyond the plane of the opposite sides of the lower jaw 15. The effective width of the upper and lower jaws 65 for exerting a shackle grip on the rail when the anchor body is pressed against the cross-tie, is defined by the vertical plane of one side of the lower jaw and the edge of the widened upper jaw which projects beyond the vertical plane of the other side of the lower jaw. With such construction, any size of bar stock may be used 70 which provides the anchor body with suitable tie bearing area and provides the desired thickness of jaws to prevent spreading thereof when the 75

Jaws are subjected to increased tension during the above mentioned shackle gripping action.

A further function of the widened upper jaw is to increase the grip of the upper and lower jaws on the rail base flange when the anchor is subjected to a turning movement about a vertical axis passing through the rail abutment surface of the shoulder 20. In such case, for example when a cross-tie is so displaced in the roadbed that the pressure of the anchor against the tie tends to rotate the jaws about the vertical axis A, an edge of the widened jaw is forced upwardly on the inclined surface of the rail base flange and thereby increases the grip of the jaw on the rail.

Referring now to the embodiment of the invention shown in Fig. 5: This embodiment is made from a somewhat heavier bar than shown in connection with Figs. 1 to 4 inclusive, and the rail engaging end of the upper jaw is the same horizontal width as the lower jaw. In all other respects the modified anchor may be and preferably is the same in construction as shown in Figs. 1 to 4. The corresponding parts of the modified device are, therefore, designated by the same reference numeral as the previous embodiment with the addition of the exponent "a".

The operation of the anchors may be briefly summarized as follows: Either embodiment shown herein may be applied to a rail by driving the hook end thereof onto the base flange of the rail until the shoulder 16 snaps up over the opposite edge of the rail base. At that time the shoulder 20 will abut against the rail base and thereby function to prevent overdriving of the anchor so that only the thin inner end of the upper jaw will overlie the thin marginal portion of the rail base flange. The outer thicker end of the upper jaw will normally receive the impact of a derailed wheel moving along the side of the rail. The thinner inner end of the jaw will bend or break under the force of such impact and permit dislodgement of the anchor. In the event that a wheel is so derailed that the flange of the wheel strikes the portion of the upper jaw which overlies the rail base, the thin portion of the jaw minimizes the punching or shearing stresses imposed on the rail flange. When the upper jaw is both flattened and widened toward its rail engaging end the increased width applies the force of the impact over a larger area of the rail base and thereby further minimizes the effect of the impact on the jaw. The widened upper jaw also cooperates with the abutment shoulder 20 to increase the grip of the anchor on the rail when the anchor is turned about a vertical axis passing through the rail abutment surface of the stop shoulder 20.

I claim:

1. A rail anchor for application to its applied position on a rail by bodily movement of the anchor transversely of the rail, comprising an under-rail body portion for abutting against a side face of a cross-tie and bent at one end into hook form to provide upper and lower jaws for gripping the top and bottom surfaces, respectively, of one base flange of a rail at a location near the edge of the flange, a rail abutting shoulder for limiting said applying movement, and means at the other end of the body for engaging the other flange of the rail base; the said upper jaw being tapered downwardly and inwardly so as to gradually decrease in thickness from the said bend toward the rail engaging end of the jaw and the major portion including the

bend of the hook being spaced outwardly from the rail abutting shoulder so as to provide a relatively long and flexible jaw the thin inner end only of which overlies and bears on the thin marginal portion of the rail base and the top surface of the thicker outer end being spaced considerably above said thin inner end whereby an impact of a derailed wheel on the thicker outer end of the upper jaw will readily distort the thin inner end thereof and thereby dislodge the anchor from the rail.

2. A rail anchor comprising a bar bent at one end into hook form to provide upper and lower jaws for gripping the top and bottom surfaces, respectively, of a rail base flange at a location near the longitudinal edge of the flange, an under-rail body portion for abutting against a side face of a cross-tie on which the rail is supported, and means for engaging both vertical edges of the rail base for maintaining the anchor in its applied position including a rail abutting shoulder at the hook end of the anchor; the said upper jaw being tapered downwardly and inwardly so as to gradually decrease its vertical thickness from the said bend toward the rail engaging end of the jaw and the major portion including the bend of said hook being spaced outwardly from the said rail abutting shoulder so that the thin inner end portion only of the jaw overlies that portion of the base flange which extends beyond the side face of the rail head and the top surface of the thicker outer end being spaced considerably above said thin inner end whereby the punching effect on the rail base is minimized when the thin inner end of the jaw is struck by a derailed wheel and whereby an impact of a derailed wheel on the thicker outer end of the upper jaw will readily distort the thin inner end thereof and dislodge the anchor from the rail.

3. A rail anchor for application to a rail having base flanges which extend beyond the side planes of the rail head, comprising a bar flattened at one end so as to gradually decrease in thickness toward the extremity and bent adjacent said flattened portion into hook form to provide upper and lower jaws for gripping the top and bottom surfaces, respectively, of one base flange at a location near the edge of the flange, an under-rail body portion for abutting against a side face of a cross-tie, and stop means on the anchor adapted to limit the applying movement thereof and the major portion of the hook being spaced outwardly from said stop whereby the thin inner end only of the upper jaw overlies the thin marginal portion of the rail base which extends beyond the side face of the rail head the said jaws being spaced apart at the bend a distance substantially greater than the thickness of the edge portion of the rail base so that the upper surface of the thicker outer end of the hook is spaced considerably above the thin inner end, whereby this higher portion only of the jaw can be struck by the tread portion of a derailed wheel.

4. A rail anchor for application to a rail having base flanges which extend beyond the side planes of the rail head, comprising a bar flattened at one end so as to gradually decrease in thickness toward the extremity and bent adjacent said flattened portion into hook form to provide upper and lower jaws, for gripping the top and bottom surfaces, respectively, of one base flange at a location near the edge of the flange in substantially the same vertical plane, an under-rail body

portion for abutting against a side face of a cross-tie, and stop means comprising a lug formed on the lower jaw adapted to engage the vertical edge of the rail base and thereby limit the applying movement of the upper jaw and the major portion of the hook being spaced outwardly from said lug whereby the thin inner end only of the upper jaw can overlie the thin

marginal portion of the rail base, and the top surface of the thicker end of the hook is spaced considerably above the short flexible portion which overlies the rail base so that this thick portion only of the hook can be struck by the 5 tread of a derailed wheel.

HAROLD G. WARR.
